UNITED STATES PATENT OFFICE.

AXEL I. S. HALVORSEN, OF ALBANY, INDIANA, ASSIGNOR TO MCCORMICK BROTHERS COMPANY, OF ALBANY, INDIANA, A CORPORATION OF INDIANA.

SUPPORT FOR FLEXIBLE DOORS OF KITCHEN CABINETS.

Application filed January 28, 1928. Serial No. 250,213.

This invention relates to supports for the flexible slat doors of kitchen cabinets. In accordance with the present invention, two supports are provided for each cabinet door, 5 each support comprising a sheet metal plate of oblong form, rounded at its ends, and having its marginal portion depressed below the body of the plate and thence flanged upwardly, forming a relatively deep oblong 10 guide groove with rounded end portions, and having a fin projecting at one side. The flange is cut away at one end, to provide a gap which will permit one edge of the door to enter the guide groove, and the fin serves 15 as a distance-piece to space the support from the top of the cabinet or compartment thereof, to prevent the door from rubbing against the top.

These supports are secured to opposite sides 20 of the cabinet by screws which pass through suitably located openings in the supports, and the supports can be quickly and accurately positioned by arranging the distance-pieces against the top of the compartment 25 and the ends of the supports against the front wall thereof.

In the accompanying drawing,

Fig. 1 is a vertical section through part of a kitchen cabinet, taken from front to rear, 30 showing one of the door supports in side view;

Fig. 2 is a section on the line 2—2 of Fig. 1, the door being partly broken away;

Fig. 3 is a perspective view of one of the 35 door supports; and,

Fig. 4 is a section on the line 4—4 of Fig. 1.

Referring to the drawing, *a* represents a cabinet having a doorway 1 and strips 2 arranged adjacent the doorway, to form grooves 3 which receive the edges of the flexible door 4. The door supports *b* and *b'* are arranged upon the sides 5 and 6 of the cabinet, in position to receive the door. As shown, each door support comprises the oblong sheet metal plate 7, having its marginal portion depressed below the body of the plate and thence flanged upwardly, as shown at 8, forming an oblong guide groove 9, straight in its central portions and rounded at the ends. A fin 10 projects outwardly from the flange 8, along one side of the support, and forms a distance-

piece for setting the support, and the flange is cut away at one end of the support, as shown at 11 and 12, to provide a gap *g* through which one edge of the door may enter the groove. The end 11 of the guide is about midway of the curved portion 8^a of the flange.

In placing the supports in the cabinet, each support is placed with its fin or distance-piece 10 against the top wall 13 of the compartment to which the door is applied, and the curved end 8^a of the flange is placed against the front wall of the compartment above the doorway 1. The support is then secured to the side wall by screws 15, which pass through the perforations 14 in the support. In these positions of the supports, the edges of the door may pass through the gaps in the flanges of the supports and into the grooves 9, as clearly shown in the drawing. The fins 10 constitute distance-pieces for spacing the supports from the shelf or top 13, so that the door will not rub against the top. When the distance-pieces are against the top 13, and the curved ends 8^a of the flanges are against the doorway, both of the supports will be positioned with their grooves directly opposite one another.

What I claim is:

1. A support for flexibly connected slat doors comprising an oblong sheet metal plate having its marginal portion depressed below the body of the plate and thence flanged upwardly, forming a relatively deep oblong guide groove with rounded end portions, the flange being cut away at one end to permit the edge of the door to pass into the groove.

2. A support for flexibly connected slat doors comprising an oblong sheet metal plate having its marginal portion depressed below the body of the plate and thence flanged upwardly, forming a relatively deep oblong guide groove with rounded end portions, and having a fin on one side extending outwardly from the flange, the flange being cut away at one end to permit the edge of the door to pass into the groove.

In testimony whereof I hereunto affix my signature.

AXEL I. S. HALVORSEN.
